HEEL CONSTRUCTION FOR CUSHION SHOES

Joseph H. Everston, Milwaukee, Wis.

Application January 26, 1935, Serial No. 3,561

16 Claims. (Cl. 36—28)

This invention relates to improvements in heel constructions for cushion shoes. The present application is a continuation in part of my application No. 699,319 filed November 23, 1933, entitled 5 Shoes. It is the primary object of the present invention to provide a cushion shoe in which a specially deep cushion is incorporated beneath the wearer's heelbone in such a manner as to absorb shock 10 and resist any tendency of the foot to slide forwardly in the shoe while at the same time the margins of the relatively nonyielding sole portions around such deep cushion are so protected and cushioned as to prevent any abrasion of the 15 wearer's foot.

I am aware that attempts have been made to provide an unusually deep cushion beneath the heelbone. It is one of the objects of the present invention to improve upon the prior art efforts in 20 this regard as to simplicity, ease of manufacture, economy, and actual achievement of the objects above specified. If the cushion material is simply enlarged in a concave depression it is necessary to mold the cushion to fit the depression, and this 25 is extremely expensive. In addition, the gradual concavity of the depression does not offer any particular resistance to any tendency of the wearer's foot to slide forward in the shoe. If, on the other hand, the margin of the deep portion of the 30 cushion is sharply defined, the shoe will be uncomfortable to the wearer.

In the present invention the margins of the opening into which a supplemental cushion is received, are sharp, and the foot is thereby prevented from sliding forwardly in the shoe, but the 35 sharpness of the margins is not sharply perceptible to the wearer because the cushion ply which extends throughout the space between the outsole and the insole is also extended across these 40 margins to soften their outlines.

It is a further object of the invention not only to resist any tendency of the foot to slide forwardly in the shoe, but also, by a modified construction, to provide support for the scaphoid 45 bone by any one of several expedients which can readily and economically be incorporated into a shoe embodying this invention.

It is another object of the invention to provide 50 simple and inexpensive means for retaining a cushion plug in an aperture of the outsole to facilitate the original lasting of the shoe, and the repair of the shoe, and also to prevent water from entering the heel of the shoe through the crevices 55 about such a plug.

In the drawing:

Figure 1 is a longitudinal section through the lower portion of a shoe containing one embodiment of the present invention.

Figure 2 is a fragmentary view in similar section through the heel portion of the shoe showing a modified embodiment of the invention.

Figure 3 is a plan view of the upper surface of the outer sole of the shoe shown in Fig. 2.

Figure 4 is a view similar to Figure 2 showing a 10 detail of a further modified embodiment of the invention.

Figure 5 is a fragmentary detail in perspective showing the sole construction illustrated in Figure 4.

Figures 6 and 7 are fragmentary details in longitudinal section through the heel portions of cushion shoes incorporating further modified embodiments of the invention.

Figure 8 is a view through the heel portion of 20 a cushion shoe in transverse section showing a still further modification.

Like parts are identified by the same reference characters throughout the several views.

The construction shown in Fig. 1 is similar to 25 that illustrated in the above entitled application No. 699,319, there being an outsole 9, an insole 10, an inseam at 11 between the upper 12 and the welt 13, a relatively inelastic filler at 14 between those portions of the insole and the outsole which are beyond the area normally occupied by the wearer's foot, and an elastic ply at 15 which 30 preferably corresponds in area to the print of the normal healthy foot as explained in the aforesaid application.

In the aforesaid companion application the outsole was skived below the heel to provide a recess having margins sufficiently sharp to constitute a well defined pocket for preventing the wearer's foot from sliding forwardly in the shoe. 40 For reasons of economy of manufacture the present construction substitutes for this skived recess a hole at 16 which is cut or punched completely through the outsole to provide a sharply margined opening in which the cushion plug 18 is received. The plug 18 rests directly upon the top lift or heel base 19 of heel 20 and is completely covered by the cushion ply 15 which also covers those portions of the outsole about the margins of the opening 16 therein. Heel 20 may contain 50 a wooden nail-retaining insert of conventional form as shown in Fig. 1.

The wearer of such a shoe has the benefit of the reduction of shock which is afforded by the cumulative effect of the cushion ply 15 and the 55

cushion plug 18, and in addition the softness of the plug allows his heelbone to sink sufficiently deeply into the pocket afforded by opening 16 so as to resist any tendency for his foot to slide forwardly in the shoe. Notwithstanding the pocketing effect of this arrangement, the wearer's heel is protected from the otherwise sharp margins of opening 18 by the general cushion ply 15 which extends across such margins.

10 All the cushions and cushion plies herein referred to may conveniently be made of sponge rubber or the like, but other forms of porous rubber or soft yieldable cushioning material may be substituted. Ordinary cork composition used as filling is not sufficiently yieldable for the purposes of this invention.

In the construction shown in Figs. 2 and 3 the resistance to forward sliding movement of the foot is increased while at the same time the shoe is provided with an orthopedic feature through the incorporation therein of a wedge 22 which may conveniently be made of leather or fiber or the like, and which includes a base portion 23 extending vertically through the forward side of opening 16 in the outsole, the wedge being then bent sharply on to the upper face of the outsole and tapered toward a flat point at 24. This wedge preferably does not project straight toward the front of the shoe, but extends toward the inside margin thereof as shown in Fig. 3 to lie beneath and support the scaphoid bone. The cushion ply 15 and the insole 10 are slightly bowed upwardly in passing over the wedge 22, as shown in Fig. 2. The margins of the wedge are softened by the effect of the cushion ply 15 so as to achieve the desired result without any discomfort to the wearer of the shoe.

In the construction shown in Figs. 4 and 5 somewhat similar results are achieved by a different location of the wedge. In this embodiment of the invention two cuts at 25 and 26 are made in the outsole 9 at the time the opening 16 is cut therein. These cuts 25 and 26 extend in a general forward direction from the opening 16 (with some inclination toward the inside of the shoe) and serve partially to sever from the outsole a tongue 27. Beneath this tongue to provide partial support therefor, is placed a special lift 30 of wedge-shaped form which may be made of rubber or the like, and which preferably terminates short of the rearward end of tongue 27 so that the rear end of such tongue is allowed to collapse to some degree into the space behind the wedge.

As in the construction shown in Figs. 2 and 3, the result of this arrangement is to increase the level of the forward portion of the heel seat beneath the scaphoid bone, and at the same time to increase the resistance to any tendency of the wearer's foot to slide forwardly in the shoe. The otherwise sharp margins of the tongue 27 are softened to the perception of the wearer's foot by the fact that they are covered by the continuous cushion ply 15.

The construction shown in Figs. 1, 6, 7, and 8 may be used separately or incorporated in any of the embodiments of the invention previously described. In each of these constructions there is means positioning the plug in the opening of the outsole, and in each instance such means may be waterproofed to resist any tendency of water to be drawn by capillary attraction into the opening 16 and pumped therefrom by the porous sponge rubber cushion up into the interior of the shoe.

In the construction shown in Fig. 6 the plug 18

is held in the opening 16 of the outsole by means of a ply of waterproofed canvas or the like which, as shown at 32, extends completely across the opening 16 beneath the plug and is marginally cemented to the under surface of the outsole to provide a complete sole. The heel base 19 is conventionally made concave and is made to accommodate such a ply.

In the construction shown in Fig. 1 and Fig. 7 a similar ply of close-grained leather or waterproofed canvas or impervious rubber or other suitable material is pressed through the opening 16 in the form of a cup 33, the upper margin being cemented to the upper surface of the outsole 9 and preferably extended to the outer margin of the heel as shown at 34. Such a cup is particularly advantageous not only in excluding water, but also in retaining the plug 18 in aperture 16 during the lasting of the shoe and during repair of the heel.

In the construction shown in Fig. 8 the plug 180 is a molded plug, provided with a radial flange at 181 which flares into the space between the top lift 19 and the outsole 9 to be engaged by the nails which hold the heel 20 in place. When these nails are driven home the flange 181 of plug 180 is subjected to substantial compression whereby it is seated tightly against the outsole to exclude moisture. At the same time its engagement by the nails prevents the plug from moving about in the opening 16 even though such opening may be larger than the actual cross section of the plug.

In all of these constructions the cushion plug at 18 or 180 is sufficiently yieldable to allow the wearer's heel to socket itself deeply in the opening 16 of the outsole, and in all of these constructions the margins of such opening 16 are completely shielded by the general cushion ply 15 which prevents them from being too sharply perceptible to the wearer's foot.

I claim:

1. In a shoe, the combination with a heel having a continuous unapertured heel base, of an outsole resting on said heel and cut away above an intermediate area of the top of said heel to provide an opening with margins sufficiently sharply defined so that the heel-bone of a wearer received therein will be restrained against any tendency to slide forwardly in the shoe, an elastic cushion resting upon the heel and disposed within the cut-away portion of the outsole to provide cushion support for the wearer's heelbone, an insole spaced from said outsole above said heel and also forwardly thereof, a counter provided at its bottom with an inturned flange disposed flat between the insole and the outsole about the heel portions thereof and a separate elastic cushioning means interposed in the space between the insole and outsole in substantially the plane of and within the flange of said counter and extending across said elastic cushion and the margins of said opening forwardly thereof, whereby to cushion elastically the margins of the cut-away portion of the outsole above said first mentioned cushion, said elastic cushion and cushioning means constituting separate layers of material one of which is positioned within the pocket of the outsole and the other of which extends continuously over the pocket and between the outsole and insole, said cushioning means providing a yieldable support for the insole and the weight of a wearer's foot thereon, and said elastic cushion and cushioning means being in direct face contact and together accumulating their

- combined effect beneath the wearer's heelbone to define a deformable area of increased elastic yielding qualities as compared with the remaining area of said cushioning means, whereby elastically to pocket the wearer's heelbone while cushioning the margins of the cut-away portion of said outsole against contact with the portions of the wearer's foot which are not thus pocketed.
5. In a cushion heel, the combination with a shoe sole apertured at the heel, of an elastically yieldable cushion socketed in the aperture, a heel base secured to said sole and extending across said aperture, and means having a portion interposed between said heel base and cushion for retaining said cushion in said aperture.
6. In a cushion heel, the combination with an outer sole having an opening at the heel, of a resilient yieldable cushion plug socketed in said opening, a heel base applied to said sole below said opening, and a relatively impervious web interposed between said heel base and said plug and having a flat portion in face engagement with said sole.
7. In a cushion heel construction, the combination with a shoe sole having an opening, of a cushion plug inserted in said opening, and a retaining web socketed to fit within said opening outside of said plug and flanged at its upper margin over the face of said sole.
8. The combination with an apertured sole and a heel applied thereto below the aperture, of a cushioned plug in said aperture provided with a radial flange interposed between said heel and sole.
9. In a cushion shoe, the combination with an outsole, an insole and a cushion ply therebetween, of means providing supplemental support for said ply solely at the forward portion of the heel whereby the heel portion of the inner sole is higher at its forward part than at its shank portion or its rearward part, said cushion ply serving to cushion the outlines of such means.
10. In a cushion shoe, the combination with an outer sole apertured at the heel, and an inner sole, of a cushion ply between said soles covering said aperture, a cushion plug in said aperture, and means applied beneath said cushion ply adjacent the forward margin of said aperture to raise the level of the heel portion of the inner sole at its forward side as compared with the level of its rearward side.
11. In a cushion shoe, the combination with an outer sole, a heel applied thereto, a cushion ply upon said outer sole, and an inner sole upon said cushion ply, of means between said heel and cushion ply for elevating the forward heel seat portion of the insole and cushion ply as compared with the rearward heel seat portions thereof.
12. In a cushion shoe, the combination with an outer sole, a heel applied thereto, a cushion ply upon said outer sole, and an inner sole upon said cushion ply, of means between said heel and cushion ply for elevating the forward heel seat portion of the insole and cushion ply as compared with the rearward heel seat portions thereof, said means comprising a wedge incorporated between said heel and outsole.
13. In a cushion shoe, the combination with an outer sole, a heel applied thereto, a cushion ply upon said outer sole, and an inner sole upon said cushion ply, of means between said heel and cushion ply for elevating the forward heel seat portion of the insole and cushion ply as compared with the rearward heel seat portions thereof, said means comprising a wedge incorporated between said heel and outsole, said outsole being formed upwardly above said wedge.
14. A cushion shoe construction comprising the combination with a shoe sole apertured in its heel portion and provided with a tongue fixed to said sole forwardly of said aperture and substantially free of said sole for vertical movement adjacent said aperture, a cushion plug in said aperture, a heel beneath said plug, a lift interposed between said heel and tongue whereby said tongue is raised above the level of adjacent outsole portions, a cushion ply covering said plug, said tongue, and adjacent portions of said outsole, and an insole on said cushion ply.
15. A cushion shoe construction comprising the combination with a shoe sole apertured in its heel portion and provided with a tongue fixed to said sole forwardly of said aperture, a cushion plug in said aperture, a heel beneath said plug, a lift interposed between said heel and tongue whereby said tongue is raised above the level of adjacent outsole portions, a cushion ply covering said plug, said tongue, and adjacent portions of said outsole, and an insole on said cushion ply.
16. A shoe heel construction comprising an outsole provided with a rearwardly directed tongue portion in the heel area, a heel below said outsole and the tongue thereof, a special lift on said heel immediately beneath said tongue, and an insole covering said tongue and adjacent portions of the outsole and elevated by said tongue and the lift therebeneath.
17. A shoe heel construction comprising an outsole provided with a rearwardly directed tongue portion in the heel area, a heel below said outsole and the tongue thereof, a special lift on said heel immediately beneath said tongue, and an insole covering said tongue and adjacent portions of the outsole and elevated by said tongue and the lift therebeneath, said lift being disposed substantially wholly forwardly of the rear free end of said tongue, whereby said tongue end yields behind said lift to render the effect thereof less abruptly perceptible.
18. A shoe heel construction comprising an outsole provided with a rearwardly directed tongue portion in the heel area, a heel below said outsole and the tongue thereof, a special lift on said heel immediately beneath said tongue, and an insole covering said tongue and adjacent portions of the outsole and elevated by said tongue and the lift therebeneath, said lift being disposed substantially wholly forwardly of the rear free end of said tongue, whereby said tongue end yields behind said lift to render the effect thereof less abruptly perceptible.
19. In a shoe construction, the combination with an outsole having a heel portion, of a special lift of limited area applied at the forward side of said heel portion, a cushion ply covering said special lift and adjacent portions of said outsole, and an insole upon said cushion ply subject to elevation at the points affected by said special lift.
20. In a shoe construction, the combination with an outsole having a heel portion, of a special lift of limited area applied at the forward side of said heel portion, a cushion ply covering said special lift and adjacent portions of said outsole, and an insole upon said cushion ply subject to elevation at the points affected by said special lift, said special lift being directed toward the inward side of said outsole.

JOSEPH H. EVERSTON.
